UNITED STATES PATENT OFFICE.

THURE DAHL, OF NEW YORK, N. Y.

DESIGN FOR A RING FOR LIGHTING FIXTURES.

Application filed December 2, 1921. Serial No. 519,518. Term of patent 3½ years.

To all whom it may concern:

Be it known that I, THURE DAHL, a subject of the King of Sweden, residing at New York city, in the county of New York and State of New York, have invented a new, original, and ornamental Design for Ring for Lighting Fixtures, of which the following is a specification, reference being had to the accompanying drawing, forming part thereof.

Fig. 1 is a fragmentary detail view of a ring for lighting fixtures showing my new design;

Fig. 2 is a bottom plan view of the same.

I claim:

The ornamental design for a ring for lighting fixtures as shown.

THURE DAHL.
